UNITED STATES PATENT OFFICE.

GEORGE ANDREWS SMITH, OF SOUTH HILL, VIRGINIA.

BOX-STUFF-TRIMMING MECHANISM.

1,314,834.

Specification of Letters Patent.

Patented Sept. 2, 1919.

Application filed January 18, 1917. Serial No. 143,153.

To all whom it may concern:

Be it known that I, GEORGE A. SMITH, residing at South Hill, in the county of Mecklenburg and State of Virginia, have 5 invented a new and Improved Box-Stuff-Trimming Mechanism, of which the following is a specification.

In the manufacture of box stuff, or what is termed in the trade "shooks", after the 10 boards are cut to the desired predetermined widths, it is usual to pile the different width boards or shooks into separate stacks, and in the ordinary way of finally edge trimming the said boards, the matcher head or 15 adjustable cutter of the planing machine is manually set to suit the requirements of the particular stack of boards to be worked, for example, if the boards in the particular stack to be worked are say four inches or 20 more wide, the matcher or cutter head is set accordingly.

In handling lumber in stacks as stated, and particularly when such lumber is to be cut up to provide shooks or box stuff, in 25 stacking the boards, different widths of boards are frequently placed in the same stack and hence in running wider boards than the predetermined size for which the planer is set, a needless waste of material 30 occurs.

Mechanical devices have been provided (see for example Patent No. 918,604 granted to me under date of April 20, 1908) that are set in operative position and controlled by 35 the board being operated on, which automatically shift the matcher or cutter head or heads to the desired predetermined positions, or in other words, if a board, say $3\frac{3}{8}$ inches wide is passing to the shiftable cutter 40 head, the latter is automatically set for edge trimming boards of that particular width and when the boards are, say $3\frac{3}{8}$ inches wide, the cutter head is correspondingly set.

In the manufacture of certain kinds of 45 boxes, those made up in standard sizes, and whose sides, ends, bottoms and top sections are made up from a combination of "shooks" of different widths, for example, $3\frac{1}{2}$, $3\frac{3}{4}$, $4\frac{1}{4}$ and $4\frac{1}{2}$ inches more or less, mechanical 50 nailers are utilized for framing up and nailing the box sections, and in the use of such mechanical nailers, it is necessary that the

several box sections be positively uniform to meet the requirements of such nailing machines, and by reason of the said requirements of mechanical nailers, it is necessary, when cutting up the rough lumber into shooks of different standard widths that they be sufficiently wider than the standard size to allow for a final trimming of the 60 edge or edges thereof without reducing the said boards or shooks below the said standard widths, for example, to allow for the final trimming, the boards should be cut about $\frac{1}{8}$ inch wider than the standard width. 65

In my Patent No. 1,204,512, the edge trimming mechanism which embodies the same general characteristics of the trimming mechanism shown in my Patent No. 918,604, before referred to, also provides for a final 70 or resetting of the cutter devices after they have been initially set by the board to be trimmed, for cutting off the extra or surplus width portion of the board.

In both machines constructed as outlined 75 and claimed in my two patents hereinbefore mentioned, the edge trimming or planing mechanism is automatically adjusted or set to the required operative positions by the different width boards as they are entered 80 into the machines or being worked on. This method of edge trimming box shooks, I have found very practical but not fully meeting all that is desired in finishing up box shooks, for the reason that the means automatically 85 set in action by the shooks to be worked are more or less complicated, are liable to get out of operative condition and require careful attention in assembling and for maintaining them at the proper operative 90 adjustments.

My present invention, which primarily has for its object to provide an improved means for edge trimming box boards, also 95 seeks to provide a machine of the general character stated, in which the operating mechanism is so combined and arranged whereby the objections noted in the use of machines in which the planing devices are adjusted by the board being trimmed, is 100 positively overcome and in which the planing or cutting mechanism remains in a relatively stationary position, with respect to the set thereof, and in which, during the

operation thereof, the board is bodily moved edgewise to the cutting mechanism as the said cutting mechanism remains in a fixed position to the board to be trimmed, during the operation of the trimming.

Another object of my invention is to provide an improved planing mechanism for edge trimming box boards of standard widths, in which is included a means for holding up the board to be edge trimmed to the planer or cutter devices and in which the board holding means is such that no special selection of any of the standard widths of boards is required when passing the boards up to be edge trimmed and which includes a simple and conveniently actuated hand controlled means for quickly adjusting the board holder for properly receiving and gripping the board to be placed thereon in position for being fed to the planing devices.

My present invention further provides certain improved attachments adapted for being readily applied to the standard types of rotary cutting disk jointing machines, and which includes manually controlled means for flatwise sustaining the board or shook to be trimmed, edgewise facing the rotary cutting disk, and a rack and latch mechanism, also hand controlled, the set of which for determining the edgewise approach of the board to the cutting disk is governed by the condition of the board edge to be trimmed, visual to the operator as he places the board in position on the board holding and shifting means, or in other words, should the edge of the board show defective portions, requiring more than the minimum forward feed for removing the extra $\frac{1}{8}$ inch surplus, the operator by manipulating the latch that engages the rack can effect a predetermined forward edgewise feed of the board to the cutting disk so as to provide for removing the initial $\frac{1}{8}$, $\frac{1}{4}$, or $\frac{3}{8}$ inches of the edge worked on and thereby, no matter how serious the defect in the board edge of an initial standard size of board, a perfect board of a proper standard width is provided.

With other objects in view that will be hereinafter stated, my present invention is an improved box stuff trimming machine that embodies the peculiar construction and novel combinations of the parts to be first described in detail, specifically pointed out in the appended claim and illustrated in the accompanying drawings, in which:

Figure 1 is a perspective view of a duplex type of box edge trimming machine that embodies my invention.

Fig. 2 is a face view of the lower half of a rotary cutting disk, and my improved attachments in co-operative relation therewith.

Fig. 3 is a top plan view of the parts shown in Fig. 2, the shiftable board holder

being shown at the outermost position and a board with a defective edge shown held thereon.

Fig. 4 is a cross section taken substantially on the line 4-4 on Fig. 3 and the board being shown in position for being advanced toward the rotary cutter disk and the stop detent about to be released to move into engagement with the selected stop notch for limiting the edgewise feed of the board to the cutting disk.

Fig. 5 is a detail end view that illustrates the rack and gear connections that slidably adjust the board holder.

Fig. 6 is a detail view of the rack and detent devices that control the selected or predetermined edgewise feed of the boards to be trimmed.

Fig. 7 is a diagram of a board to be trimmed to a standard size and having a defective edge that extends back beyond the $\frac{1}{8}$ surplus width on the edge to be trimmed.

Fig. 8 is a similar diagram that illustrates the amount of board edge that needs to be trimmed off to bring the defective board down to a next standard width.

Fig. 9 is a detail view of the rack and detent devices, the pawl being shown in position for stopping the forward feed of the board.

Figs. 10 and 10^a are plan views that illustrate a modified arrangement of the stops on the board projecting or pusher frame.

Since in practice it is usual to build jointer machines with a cutting disk at each end of a driven shaft and provide a co-operative board holding means for each cutting disk, I have illustrated my invention as applied to each of the oppositely disposed cutting disks, as shown in Fig. 1, it being understood that the following detailed description of the operating parts apply to the board edge trimming mechanism at one side only.

In the drawings, 1 designates the main framing of a box board jointing machine, in the oppositely disposed upright portions 2-2 of which is journaled a horizontal shaft 3 upon each end of which is mounted a rotary disk cutter 4-4, said cutters being located outside of the dust and shavings blower casings 5-5, the said parts being of a well known construction and form *per se* no part of my present invention.

7-7 designate a pair of oppositely disposed brackets that project from one end of the main frame and 8 denotes what I term a shearing bar or chip cutter whose opposite ends are fixedly mounted on the inner top surfaces of the brackets 7-7, whereby to provide for setting the said bar 8 up close to the face of the cutting disk and provide a solid base bearing for the inner edge of the board to be trimmed.

80 designates a pendent yoke member that

is fixedly attached to or integral with the bar 8 to which is fixedly connected an outwardly extended horizontal bar 9, the purpose of which will presently appear.

- 5 10 designates what I term the pusher or board projecting frame and the said frame includes a cross bar 10^b formed at the center with a pendent U-shaped portion and provided at the opposite ends with open bottom bearings 10^a—10^a for slidably riding upon the outer squared ends 70—70 of the bracket, the under faces of which have cog racks 71—71, as is best shown in Fig. 5.
- 10 11 designates a shaft that extends across the front of the main frame and is journaled on the side arms of the U-shaped portion 12 of the cross bar 10^b and the said shaft carries cog gears 13—13 at the opposite ends that are held in mesh with the cog racks 20 71—71 on the brackets 7—7.

- 14 designates the hand wheel on one end of the shaft and 14^a a collar that is secured upon the said shaft between the U-shaped portion 12 of the frame 10 to hold the shaft 25 against longitudinal displacements.

By referring to Fig. 2, it will be noticed that the top of the cross bar 10^b and the upper face of the shearing bar 8 are in the same plane and the said surfaces form the 30 bearing for the boards to be trimmed, that edge of the board to be trimmed resting on the bar 8 as it is being engaged by the planer knives α of the rotary cutting disk.

Adjustable stops 15 are mounted on the 35 cross bar 10^b against which the larger edge of the board to be trimmed is set when it is placed in position for being fed up to the planer devices.

By reason of the coöperative arrangement 40 of the parts so far described, it is obvious that the board projecting frame can be conveniently slid back and forth, relatively to the cutter disk, by properly manipulating the hand wheel on the shaft 11, the rotation of which, in either direction, through 45 the gear connections with the rack 70—70 on the brackets 7—7 slides the frame 10 in either desired direction, and by reason of such convenient means of setting the frame 50 10, it is not necessary to stack the different standard sizes of the boards preparatory to putting them in position to be trimmed, since in picking up the boards and placing the same in position, the operator manipulating the shaft hand wheel, sets the frame 10 to suit the width of board picked at random from the board pack.

The advantages of being able to quickly 55 adjust the board projecting frame 10 to suit the width of the board as stated is apparent, since it avoids the more or less expensive means heretofore provided for assorting and stacking necessary when finishing up "shooks". As before noted, the requirements in the manufacture of standard

sizes of shooks provides for a perfect assemblage of the boards when worked up into boxes of standard sizes and makes it necessary to leave a surplus width of board over the standard widths to allow for finishing up the shook edges after reducing them below the desired standard sizes. 70

In my present invention, I employ a simple rack and pawl mechanism for controlling the trimming off of the said surplus 75 or trimming width and also regulating the edgewise feed of the board to the cutting disk to take care of boards having defective edges, or in other words, boards having knot holes, notches or chip portions of such 80 proportions that they extend inwardly beyond the "surplus" edge allowed for trimming.

The rack and pawl mechanism best shown in detail in Fig. 5, comprises the bar 9 heretofore referred to that projects horizontally forward from the pendent yoke portion 80 on the shearing bar 8 and which, as shown, is located in line with the U-shaped portion of the frame 10 and the said bar 9 has a 90 series of ratchet teeth 17 which, in practice, are $\frac{1}{4}$ an inch long and with which normally engages a detent or pawl 18 that is pivotally mounted on the yoke of the frame 10 and is formed with an outwardly extending finger 95 18^a.

19 is a spring that tends to normally hold the detent or pawl in engagement with the rack, it being understood as the frame 10 is moved outwardly in position for receiving 100 a new board, the detent pawl 18 slips over the ratchet teeth 17.

At this point, it should be stated that the relative arrangement of the gear mechanism for shifting the frame 10, the pawl 18 and the ratchet teeth 17, is such that normally the heel 18^b of the pawl 18 sets back from the locking edge 17^c of the ratchet teeth on which it rests, a distance of $\frac{1}{8}$ an inch to allow for the required forward feed of the 110 board edge when trimming off the surplus $\frac{1}{8}$ inch width, to thereby reduce the board width to the proper standard size, or in other words, if the board being worked on is 3 $\frac{1}{2}$ inches wide, after being edge trimmed it 115 will be of such width.

Another and advantageous feature developed in providing the rack and pawl mechanism shown, is should the edge of a board of a standard width, say 3 $\frac{1}{4}$ inches 120 wide, be defective, it at once becomes apparent to the operator when he places the board in position for being trimmed, the operator can conveniently provide for trimming off the defective edge and to bring the 125 defective board down to the standard size next below that to which it was originally cut.

To make this clear, attention is called to Fig. 8 which diagrammatically shows a 130

board of say $3\frac{3}{4}$ inches wide with the surplus edge portion indicated by y and with defective portions designated a that extend inwardly beyond the edge portion y .

When placing a board, such as indicated, in position, the operator notices that the defects extend beyond the trimming line y and as he feeds the board forward, he trips the pawl 18 out of engagement with the ratchet teeth with which it was held and holds it out until it passes over the next forward tooth and in releasing it, the spring throws the said pawl 18 into the said next forward tooth to provide for an extra $\frac{1}{4}$ inch edgewise projection of the board to the cutting disk and thereby provides for trimming the board with the finished board to a $3\frac{1}{2}$ inch width.

The advantages in taking care of the defective edge boards in the manner stated is apparent to those skilled in the art to which my invention relates, in that it saves the time in throwing aside a defective board and handling it for a resaw to reduce it to a lower standard width.

My present means for handling and edge trimming box boards saves assorting the different widths, facilitates the trimming operations, and avoids the necessity of more or less complicated mechanism for setting the planer or matcher head.

Among other advantages in the practical application of my present means for trimming board edges, is that as some of the stock received at the mill is cut with one edge bias, in the ordinary handling of box stuff boards or shooks a great waste occurs when trimming such shapes of boards to any standard size.

With my present means for trimming board edges, boards of the shapes shown in Figs. 10 and 10^a can readily have their bark or irreg-

ular edges trimmed down to predetermined limits, depending upon the character of the said rough edge, and the boards thus trimmed sized to match for making a box top, bottom, side or end.

To provide for working boards having one edge cut bias, as stated, the stops 15—15 are adjustably mounted on the pusher bar 50 10^a, as shown in Figs. 10 and 10^a, and are arranged for being adjustably set so that the operator by adjusting the said stops 15, (see Figs. 10, 10^a of the drawing) can provide for the required feeding of the board 55 to the desired limits, toward the cutting disk the same as when trimming boards with relatively parallel opposite edges, as shown on Fig. 3.

The advantage in providing for trimming 60 boards shaped on the lines indicated in Figs. 10 and 10^a will be understood when it is considered that in the present handling of boards of such shape, the bias edge must be first ripped off, to bring such edge in parallelism with the other edge before the board 65 can be finally edge trimmed.

What I claim is:

In a board edge trimming machine, the combination with an edge planer; of means 70 for holding the board to be edge trimmed at right angles to the planer, the said means comprising horizontally disposed opposite rack bars, a carriage slidably mounted on the rack bars, pushers mounted on the carriage that form stops for the outer edge of the board to be trimmed, the carriage including pendent members, a shaft journaled at its opposite ends in the said pendent members, and gears on the said shaft engaging the rack faces on their respective end 75 guide bar.

GEORGE ANDREWS SMITH.
